BOAT

Pierre Ernest Mercier and Raymond Villers-Allemand, New York, N. Y.; said Mercier assignor to said Villers-Allemand

Application August 10, 1945, Serial No. 610,070

8 Claims. (Cl. 9—1)

1.

Our present invention comprises a new boat or hull construction particularly suitable for use in small pleasure craft whether hand, sail or motor propelled.

An object of the invention is to provide a simple and inexpensive boat that is buoyant, stable and seaworthy.

A further object of the invention is to provide a boat construction utilizing few parts.

Still another object of the invention is to provide a boat having a deformable hull to absorb and minimize the shocks incident thereupon by the action of the water.

Other objects of this invention will be apparent as the description proceeds.

For an understanding of the invention reference may be had to the accompanying drawings of which—

Fig. 1 is a top plan view, partly broken away, of a boat constructed according to the invention,

Fig. 2 is a vertical longitudinal sectional view taken on the line 2—2 of Fig. 1,

Fig. 3 is a staggered vertical transverse sectional view taken on the line 3—3 of Fig. 1; and

Fig. 4 is a vertical transverse sectional view of a boat representing another embodiment of the invention.

In accordance with the invention, the new boat or hull construction comprises a pair of orthogonal frames, one the deck frame and the other the keel frame, an outer inelastic flexible skin secured to or surrounding the frames, and pneumatic means, comprising inflatable tubes or the like, which when inflated are forced against the skin; the pneumatic means, together with the frames causing the skin to take a shape determined by the relative dimensions of the frames, the area of the skin and the location of the engagement of the inflatable means therewith. It will be apparent from the foregoing brief outline of the essential elements of the new boat construction, that the invention may be embodied in various types of boats.

In the embodiment of the invention illustrated in Figs. 1 to 3 the orthogonal frames comprise the deck frame 2 and keel frame 4. As shown best in Fig. 3, the deck frame 2 is formed from three sheet elements 2a, 2b and 2c. Element 2a is a flat sheet or strip of relatively narrow width the outer edge of which defines the periphery of the deck and the inner edge of which is riveted to the elements 2b and 2c. Elements 2b and 2c each comprise sheets or strips having two right angle bends therein to provide vertical reinforcing wall portions and horizontal outer portions

extending over and spaced from the element 2a. The element 2a, at the forward end of the frame extends well beyond the elements 2b and 2c to form a bow deck section. Short tubular elements 2d are secured at intervals along the deck frame for reception of strut parts of the keel frame, as hereinafter described. A tubular reinforcing member 2e for the stern of the boat is connected between the rear pair of elements 2d. The inner periphery of the deck frame 2 defines an opening 6 which may be covered by removable deck sections 8.

The sections 8 may be of canvas if desired, in which case they are securely but removably fastened to the frame 2 by any suitable means. For example snap fasteners indicated diagrammatically at 8a, could be employed.

The keel frame 4 comprises the longitudinal part 4a connecting at the stern with tubular struts 4b which are angularly disposed with respect to the part 4a and terminating at the bow in an upwardly extending part 4c for attachment to the bow deck section of the deck frame element 2a, and a plurality of pairs of tubular strut members 4d secured to the part 4a and adapted to be received in and secured to the tubular elements 2d of the deck frame.

The number of struts 4d will depend, of course, upon the length of the boat. For the type of boat illustrated in Figs. 1 to 3, four pairs of struts 4d will give sufficient rigidity to the completed boat. The struts 4d, as shown best in Fig. 3 are arcuate in shape with their concave sides facing the sides of the boat. Spaced longitudinally along the boat are a plurality of pairs of straps 14 of strong non-elastic material, which are secured at their ends to the part 4a of the keel frame and the element 2a of the deck frame. These straps 14 are each of a length about equal to that of a strut 4d and, together with crossing straps 14a, form a network for forcing the inflatable members against the inextensible skin of the boat. The inflatable members comprise tubes 16 of rubber or the like which are disposed longitudinally of the boat externally of the straps 14, 14a and struts 4d and internally of the skin 18. The skin 18, is made of canvas or the like, suitably treated to render it water-proof and made from a sufficient number of pieces, sewn or otherwise secured together, so as to have the desired hull contour when made taut by the pressure of the tubes 16.

Preferably a reinforcing longitudinal member 18a, adapted to fit snugly over the keel part 4a, is secured, as by rivets, to the inner surface of

the skin 18 along the longitudinal median line thereof to anchor the skin to the keel frame when the boat is assembled. A hem 20 is provided around the periphery of the skin through which is threaded a draw string 22 of metal wire.

In assembling the above described parts of the boat, the two frames 2 and 4 are first secured together as by insertion of the struts 4b and 4c into the tubular members 2d of the deck frame and the bolting of the forward end 4a of the keel to the bow deck part of element 2a. The straps 14 are then secured at their ends to the keel part 4a and the deck element 2a; these parts being provided with suitable holding means for the straps 14, as for example the longitudinal stringers indicated at 12.

The tubes 16, deflated, are laid within the skin 18, at opposite sides of the member 18a, the joined frames 2 and 4 are then inserted into the skin with the keel part 4a within the longitudinal member 18a. The draw string 22 is then tightened in the hem 20 to pull the hem and string into the channel 10 formed between the elements 2a and 2b of the deck frame.

The tubes 16 are then inflated by usual means (not shown) to force the skin into the desired contour, the channel 10 anchoring the skin around its periphery. The skin at the bow of the boat as shown best in Fig. 2, extends over the forwardly extending part of element 2a. In order to insure that the skin will be taut and firmly anchored in the channel 10, a plate member 24, which may be moved forwardly as by screw means 26, is provided in the channel 10 at the bow of the boat.

Thus after the parts are assembled, the wall portion 24 may be forced against the string to increase the tension thereof. Alternatively the hem 20 and string 22 could be omitted and the edge of the skin riveted and glued to the deck frame prior to inflation of the tubes 16.

In the embodiment of the invention illustrated in Figs. 1 to 3, two longitudinally disposed tubes 16 extending the length of the boat have been shown. Obviously more tubes could be employed if desired, or a single, closed, generally oval shaped tube could be employed if desired. Preferably several separate tubes are provided to minimize the danger of deflation in the case of puncture.

In the embodiment of the invention above described, the boat will be substantially flat bottomed, or somewhat reentrant along the keel 4a dependent upon the width of the skin 17 and degree of inflation of the tubes 16 relative to the vertical distance between deck and keel. The keel will be sufficiently heavy, either because of the material and dimensions thereof, or if necessary by the addition of strategically placed weights, to cause a substantial part of the hull surface to be submerged, as indicated by the water lines in Figs. 2 and 3. The boat will be seaworthy and extremely light and because of the flexible skin thereof, combined with the inflatable tubes 16 therein, will deform sufficiently when in use and subjected to the action of the waves to minimize shocks to the boat and its occupants.

In Fig. 4 is illustrated an embodiment of the invention in which the external contour of the hull has a double curvature. The boat of Fig. 4 differs from that of Figs. 1 to 3 in that suitably spaced centrally disposed vertical struts 28, connected to transverse strengthening members 30 of the deck frame 2 are employed instead of the pairs of arcuate shaped struts 4d of the keel frame of Figs. 1 to 3 and in that the straps 32,

corresponding to the straps 14, are secured at their lower ends to longitudinal stringers 34 carried by the skin 18. These straps 32 confine the tube 16 to the upper portions of the hull, causing the skin to curve outwardly wherein contact with the tubes and to curve inwardly under the tension of the straps on the stringers 34. The resulting hull contour of double curvature is one particularly suitable for racing craft as the hull will cut through the water with a minimum of resistance.

The invention has now been described with reference to two embodiments thereof. In neither embodiment have we illustrated any propulsion means as obviously any suitable means, whether manual, sail or power driven could be employed and such means form no part of our invention. In each embodiment of this invention a flat deck only has been indicated. Obviously any suitable superstructure could be added if desired or openings in the deck could be provided for the occupants' feet or for storage purposes. Also, the keel frame could be constructed, if desired, to include suitable provision for the usual center board. As heretofore indicated our invention is concerned only with the novel hull structure heretofore described and defined in the appended claims and not with auxiliary details suitable only for a particular type of boat.

We claim:

1. A boat comprising a keel frame, a deck frame secured to said keel frame at spaced points, an inextensible flexible skin enclosing said frames and forming the outer walls of the boat, longitudinally disposed inflatable members below the deck frame and within the skin and inextensible flexible members intermediate said inflatable members for forcing the same when inflated against the skin member whereby the walls of the hull of the boat may have a predetermined contour.

2. The boat according to claim 1 wherein said last mentioned members comprise a plurality of longitudinally spaced straps, each strap being secured to the keel frame at one end and at the other end to the deck frame.

3. The boat according to claim 1 wherein said last mentioned members comprise a plurality of longitudinally spaced straps, each strap being secured at one end to the deck frame and at the other end to the skin below an inflatable member whereby the hull will have a double curvature contour, said skin being reinforced longitudinally along the lines of attachment of the straps thereto.

4. The boat according to claim 1 wherein said deck frame is provided with a substantially peripheral groove for reception of the upper edge of said skin, means including a draw string for anchoring said skin in said groove and a movable wall portion carried by the deck frame for increasing the tension of said string in said groove.

5. A boat comprising a longitudinally disposed frame member forming a combined keel, bow and stern, a horizontally disposed frame forming a deck member, spaced struts forming part of said keel member and secured to said deck frame, a network of flexible strap members connected between the deck frame and the keel frame, an inextensible skin member of flexible material enclosing said frames and forming the side walls of the boat and inflatable members between said strap members and said skin member.

6. A boat comprising a deck member, a keel member secured to said deck member so as to

extend substantially perpendicular thereto an inelastic skin of flexible material enclosing said members, inflatable members adjacent the inner walls of said skin for forcing said skin taut to form a hull for the boat, and a member secured to the inner surface of said skin along the longitudinal median line thereof for engaging the keel member and preventing relative movement between the skin and the keel.

7. A boat comprising a deck frame provided with a substantially peripheral groove, a keel frame secured to said deck frame, said keel frame including pairs of strut members secured to the deck frame at opposite sides thereof, a network of straps secured between said deck frame and said keel frame, a flexible inelastic skin fashioned to form, when taut, the hull of the boat, and having an opening for insertions of said frames therein, said skin being provided with a hem and draw string around the periphery of its opening, and inflatable members between said network and said skin which when inflated are forced against said skin by said network, said draw string and hem entering and being anchored in said groove when said string is tight and said members are inflated.

8. The boat according to claim 7 including a movable element forming a portion of the wall of said groove and means for forcing said element against said string to increase the tension thereof.
